DYNAMITE PRIMER CARTRIDGE

Lawrence W. Early, Wilmington, Del., assignor to
 Hercules Powder Company, Wilmington, Del.,
 a corporation of Delaware

Application October 12, 1939, Serial No. 299,161

4 Claims. (Cl. 102—27)

This invention relates to an improved explosive primer and more particularly to an improved explosive primer tube including a tube containing a firing device and of such size as to receive a cartridge of explosive.

As is well known, the established method of the art for firing explosive charges is by the use of blasting caps inserted into one of the cartridges of the explosive that makes up the charge. Explosive charges so fired may be large or small and of any of the various commercial types such as, for example, straight or extra dynamites, gelatins, permissibles, or the like. The blasting cap used is either fired electrically or by a fuse and may be either of the instantaneous or delay type. This combination of a blasting cap in conjunction with a cartridge of dynamite is called a primer by the art.

In many operations the primers, described above, are made up at a point remote from the shooting face to provide an added degree of safety and to effect a saving in loading and firing time. In other operations it is necessary, due to company rules, local laws, etc., to take the dynamite and caps to the shooting face separately and there prepare the primers. This type of operation consumes time and under many conditions is considerably more dangerous than the use of prepared primers.

It is the object of this invention to produce an improved primer. A further object of the invention is to produce a primer tube in which is positioned a firing device. A still further object of this invention is to prepare a primer tube of sufficient size to allow the insertion of an explosive cartridge. A still further object of this invention is to produce a primer tube that facilitates the quick preparation of an explosive primer. Other objects will appear hereinafter.

The objects of this invention may be accomplished by producing a tube of such size in relation to diameter and length that a particular explosive cartridge may be easily but snugly inserted therein. The primer tube, in general, may include a rigid outside member and an inside member which conforms to and holds a blasting cap securely against the inside surface of the outside member. The blasting cap is therefore positioned securely between two layers of material and will further, upon the insertion of a dynamite cartridge be in close contact with the dynamite. To provide more positive contact of the detonating part of the blasting cap with the inserted dynamite cartridge the inside member is cut in such a manner that the detonating part

of the cap is exposed to the dynamite cartridge. Alternately, the outside tube may be slotted and the blasting cap threaded therethrough to effect the positioning instead of using two layers of material. Thus, the cap is positioned without the use of an inside member.

Having now indicated in a general way the nature and purpose of this invention, there follows a more detailed description of preferred embodiments thereof, with reference to the accompanying drawings in which like numerals refer to similar parts of the drawings.

Figure 1 is a cross-sectional view of the primer tube with a delay electric blasting cap fastened securely in position. Figure 2 is an end view of Figure 1. Figure 3 is an elevation view of the primer tube with a delay electric blasting cap in position and with the leg wires of the cap packaged within the tube. Figure 4 is a cross-sectional view along line 4—4 of Figure 3. Figure 5 is an elevation view of a primer tube with a delay electric blasting cap in position and a dynamite cartridge inserted within the tube. Figure 6 is a cross-sectional view along line 6—6 of Figure 5. Figure 7 is a cross-sectional view of a primer tube with a delay electric blasting cap threaded therethrough. Figure 8 is an end view of Figure 7. Figure 9 is a side elevation view of a primer tube with a delay electric blasting cap threaded therethrough and with a label thereon, a part of the label being removed to show the portion of the primer tube with the blasting cap therein. Figure 10 is an end view of Figure 9.

To facilitate a clear description of this invention, the primer tube will be described without a dynamite cartridge inserted therein such as is shown in Figures 1 and 2. In Figures 1 and 2 the primer tube 1 includes an outside tube 2 of paper, cardboard, plastic, or fiber construction and fitted inside this tube 2 there is a similar second or inside tube 3 so constructed and shaped as to fit snugly therein and to provide a tubular recess 4 into which an electric blasting cap 5 may be inserted. It will be noted that the inside tube is so formed at point 6 as to allow exposure of the detonating section 7 of the blasting cap 5. Thus, this exposed section 7 of the blasting cap 5 will, upon insertion of a dynamite cartridge, be in close contact with the dynamite and will insure positive detonation of the entire explosive charge. The blasting cap 5 may be held in place by pouring a sulfur plug 8 around its upper section as indicated. To reduce the possible obstruction that the inside tube 3 may offer to the insertion of a dynamite cartridge, the end has been tapered as

shown. Such a taper may best be visualized by passing a vertical plane downwardly through the tubular member at an angle to the longitudinal axis thereof, the line of intersection between the plane and the tubular member providing the taper desired. In the event the tubular member is made from a flat rectangular piece of material adjacent corners of said pieces of material adjacent one end thereof may be beveled inwardly. When such material is formed into a tube, the desired tapered end will be provided. It will be evident, of course, that all portions of the outer surface of this tube will fit snugly within the outside tube. When a cartridge is inserted into the assembled primer, it will encounter the tapered portion of the inside tube and can be quite readily pushed past said tapered portion. In the event no taper is provided an inserted cartridge will abut a continuous ridge formed by the end of the inside tube, such ridge offering considerably more resistance to continued inward movement of the cartridge than would the tapered tube. It will be understood that this inside tube 3 may also be the same length as the outside tube 2, as in Figure 5, or may be cut shorter, as in Figure 3, the design of the said tube merely facilitating the efficient retention of the blasting cap in its proper place and aiding in allowing the easy insertion of the dynamite cartridge into the assembled primer tube.

In Figures 3 and 4 there is shown a modification of this invention which includes a convenient means of packaging the leg wire 9 of the electric blasting cap 5 for shipment of the primer tubes. Thus, the primer tube 1 similar to the tube shown in Figure 1 includes an outside tube 2 and inside tube 3, placed to hold an electric delay blasting cap 5 in position. The leg wires 9 of the cap 5 are folded in the conventional accordion fold and the bundle inserted within the primer tube 1. The leg wires 9 may, if desired, be tagged to indicate the delay period of the delay blasting cap 5 used in the device, or the delay period may be printed on the outside of the primer tube itself. The length of the leg wires 9 and the size of the primer tube 1 will, of course, effect the method of packaging but such adjustments are, as will be apparent, contemplated. Thus, for example, if the lead wires are too long and/or too bulky to be packaged inside the tube 1, they may be packaged on the exterior of the tube in any suitable manner.

Figures 5 and 6 indicate how the primer tube 1 of this invention is to be combined with a dynamite cartridge 10 to quickly effect the construction of a primer ready for use in any explosive operation. Thus, the bundled leg wires 9, shown in Figure 3, are removed from the inside of the tube 1 and a dynamite cartridge 10 is inserted into the tube 1. The size of the tube 1 and the size of the dynamite cartridge 10 are coordinated so that the cartridge 10 is easily slipped into the tube 1 but in such a manner that a snug fit is maintained and close contact is produced between the dynamite cartridge and the detonating section 7 of the blasting cap 5.

In Figures 7 and 8 there is shown a modification of this invention which discloses a means of joining the firing device to the tube without the need of using a tube of double thickness. Thus, the primer tube 1 includes only an outside tube 2 and the electric blasting cap 5 is inserted through the wall of this tube 2 with a threading motion. The tube 2 is slotted at points 11 and the firing device is enclosed within the tube at points 12 and ex-

posed to the outside at points 13. In all cases the detonating end of the firing device will be positioned so that it may contact the explosive cartridge. In some cases it may be necessary to cut away a portion of the tube to expose the detonating end of the firing device to contact with the explosive cartridge. To hold this firing device in position, glue or other adhesives may be used between the tube and the firing device. It will be apparent that the wires of the cap in this embodiment may be packaged in the ways described hereinbefore.

In Figures 9 and 10 an additional variation of this invention is shown. Thus, the primer tube 1 includes an outside tube 2 through the wall of which the firing device 5 is threaded. This threading procedure is described with reference to Figure 7. The tube 2 after the firing device 5 is in position is wrapped with a label 14 which may entirely cover the outside of the tube 2 although it should be appreciated that in some instances it may be desirable to cover only that portion of the tube in which the firing device 5 is positioned. The label 14 snugly engages the outer surface of the tube 2 including the portions 12 which embrace the outer portions of the firing device, and thus aids in re-enforcing the primer tube and in retaining the firing device in position. The label may also cover the detonating end of the firing device if the threading operation leaves it exposed.

In these Figures 9 and 10 the tube is also shown to contain a split 15 along its longitudinal axis. This splitting of the tube allows the tube to be used with explosive cartridges of various diameters and in no way effects the priming efficiency. The split tube will maintain its position about the explosive cartridge in a positive manner and gives results equal to the tubes without the split. Thus it is possible to place a primer tube having, for example a diameter of 1 inch on explosive cartridges having diameters from 1 to 2 inches. This expedient aids operations by reducing the different size tubes which must be stocked. It will be obvious that the label may, if desired, cover the longitudinal split. This tube may be used with larger diameter cartridges by simply tearing or breaking the label to allow opening the tube to receive the cartridge.

The primer tube of this invention may be made from a variety of materials such as, for example, paper, cardboard, plastics, fiber, or similar materials which may be shaped in the form of a tube. I have found that the preferable embodiment of my invention includes a tube prepared from 2 ply .016" test liner paper as such material is sufficiently rigid to withstand the necessary abuse and is also economically feasible. It will be apparent that if I use a fiber or plastic, the tube may be so molded as to have a recess for the blasting cap or I may use an inside sleeve of the same material or any other convenient material to retain the blasting cap in position. Also, the inside tube may be formed from flat stock and shaped to the design wanted, inserted into the tube, and glued or otherwise fastened into place. This inside tube may be designed to expose the detonating section of the blasting cap as described hereinbefore or may cover the entire cap, the detonation of the dynamite being effected through the cap covering. If the tube is to be of single thickness with the blasting cap threaded therethrough it may be desirable to use a heavier test liner paper but this variation is well within the skill of the art.

In the foregoing description, the blasting cap used in the primer tube of this invention has been of the delay type, but it is to be understood that there may be used any of the various commercial electric firing devices such as, for example, delay electric blasting caps, delay electric igniters, electric blasting caps, fuse blasting caps in special cases, and electric squibs when black powder is to be fired.

In the manufacture of these devices, two tubes of the same diameter may be used because the crimping of one tube to provide a recess for the blasting cap decreases the diameter of the tube so that a close fit is obtained between the two tubes. I also contemplate cutting sufficient material from the inside tube to provide the proper fit between the inside and outside tube. This may be accomplished by cutting and removing a longitudinal section of material from the peripheral portion of the inside tube. Thus, just sufficient material is removed to permit a close fit between the inner and outer tubes with the ends of the cut portion in abutting relation. Further, this inside tube may be, as described hereinbefore, manufactured from flat stock and formed and placed inside the outside tube. Any such deviations of construction will be apparent to those skilled in the art and are understood to be within the scope of this invention. I have found that it is very desirable to fasten the two tubes together by any convenient means, the preferable means being to glue the two sections together. The use of the blasting cap threaded through a single thickness tube does away with the trouble of joining the double tubes described above. It may be desirable in some cases as a further aid in holding the entire assembly together, and also to aid in the waterproofness of the device, to dip the prepared tubes into molten paraffin, rosin-paraffin, and mixtures of similar materials, either before or after assembly.

In order to positively position the blasting cap in its recess, a small amount of material such as, for example, glue, rosin, plastic, or molten sulfur may be poured into the tubular recess and allowed to harden. It will be obvious that when cutting the tube to provide unrestricted contact between the section of the blasting cap containing the detonating charge and the dynamite cartridge, the type of blasting cap to be used, especially as to length, must be considered. To accomplish the same result, the inside tube may be definitely placed so that the explosive end of the cap will at all times be in one position and thereby allow the non-explosive part of the cap to vary in position.

Since the primer tubes of this invention require the insertion of a dynamite cartridge before they are ready for loading, they are more useful where it is necessary to prepare primers quickly as, for example, at a tunnel face. The insertion of a dynamite cartridge in the primer tube of this invention is obviously a much simpler and easier means of preparing primers than the method of making a hole in the dynamite cartridge, inserting a blasting cap therein, and taking the necessary precaution to prevent the cap from being pulled out of the cartridge during the bore hole loading operations.

The advantage of my improved primer in tunnel work is of major importance as in some districts blasting caps and dynamite are not permitted to be transported into the tunnel together. This ruling precludes the possibility of transporting to a tunnel face the normal blasting

cap-dynamite cartridge, known to the art by the term "primer" and which is used in this sense in the present specification and claims.

Therefore, it is necessary for operators to carry blasting caps to the face of a tunnel then bring dynamite to the face and prepare the blasting cap-dynamite cartridge primers. This operation is time-consuming and dangerous. The use of the primer tubes of this invention alleviates this condition due to the ease, quickness and simplicity of preparing primers from the primer tubes of this invention. Further, it requires less skill to prepare and use the device of this invention than regular primers.

15 Although my primer tubes are especially advantageous in tunnel work, their use will also be found advantageous in any explosive work where the necessity of preparing primers from a blasting cap and cartridge of dynamite is a prerequisite to blasting.

20 The primers prepared from the primer tubes of this invention may be used in exactly the same manner that a primer made by inserting blasting cap into a dynamite cartridge; therefore, my primers may be substituted in any explosive work and their attendant advantages of ease, quickness, and simplicity of assembly enjoyed.

25 It will be understood that the details and examples given hereinbefore are illustrative only, and in no way limiting on my invention as broadly described hereinbefore and in the appended claims.

30 What I claim and desire to protect by Letters Patent is:

35 1. A priming device adapted to receive and prime an explosive cartridge comprising an outer paper tube, an inner paper tube snugly fitted within the outer paper tube, said inner paper tube being provided with an inwardly extending portion forming a tubular recess, said recess extending longitudinally of the inner tube, a firing device positioned in said recess and securely fastened therein, said firing device having a detonating end extending from the recess into the 40 interior of the inner tube whereby when an explosive cartridge is inserted into the inner paper tube the detonating end of the firing device will be in priming contact with the cartridge.

45 2. A priming device adapted to receive and prime an explosive cartridge comprising an outer tubular member, an inner tubular member snugly fitted within the outer tubular member, a longitudinally extending recess in said inner tubular member consisting of an inwardly pressed portion of the peripheral surface of said member, the inner end of said inner member being tapered to facilitate entrance of a blasting cartridge into the device, an electric firing device positioned in said recess and held therein by the outer tubular member, said firing device having a detonating end projecting from the recess into the interior of the inner tubular member, whereby when an explosive cartridge is inserted into the primer the detonating end of the firing device will be in priming contact with the cartridge.

50 3. A priming device adapted to receive and prime an explosive cartridge comprising a shock-resistant tubular member, said member having a series of transverse cuts dividing a longitudinally 55 extending portion of the surface of said member into a plurality of relatively movable sections, an electric firing device threaded through said sections so that one section passes above the firing device and the adjacent section below it, said firing device having a detonating end extending into

the tubular member whereby when an explosive cartridge is inserted into the primer the detonating end of the firing device will be in priming contact with the cartridge.

4. A priming device adapted to receive and prime an explosive cartridge comprising a longitudinally split tubular member, a series of transverse peripheral cuts in said member adjacent one end thereof, said cuts dividing a longitudinally extending portion of the surface of the tubular member into a plurality of relatively movable

strips, an electric firing device threaded through said strips in a manner such that one series of alternate strips pass under the firing device and another series of alternate strips pass over the firing device, said firing device having a detonating end projecting into the tubular member and a label wrapped around said tubular member and firing device and aiding in holding them in assembled position.
